UNITED STATES PATENT OFFICE

ALBERT W. BRUCE, OF OTTUMWA, IOWA, ASSIGNOR TO BARKER POULTRY EQUIPMENT COMPANY, OF OTTUMWA, IOWA, A CORPORATION OF IOWA

BROODER VENTILATION STRUCTURE

Application filed November 12, 1930. Serial No. 495,163.

An object of my invention is to provide a brooder ventilation structure of simple, durable and comparatively inexpensive construction.

5 A further object is to provide a structure in which crates are provided for fowls and a ventilation system is so arranged with respect to the crates that fresh air passes over all the fowls in each crate and is then discharged outside of a closed chamber in which the crates are located. Such a construction causes all the air that has been breathed out by the fowls to be exhausted from the closed chamber instead of being discharged there- 10 into and re-breathed by any of the fowls, with the result that each fowl receives absolutely fresh air, which of course promotes the health of the fowls and by actual test has been found to increase their weight over a 15 given period, when compared with the weight of fowls which re-breathe the air in the brooder structure. Such a system of ventilation also prevents the transmission of disease from one fowl to another or from the fowls 20 in one of the crates to a fowl in another crate, since none of them re-breathe the air exhaled by another fowl.

A further object is to provide a ventilation system which promptly carries off all 25 odors, as well as the exhaled air from the fowls.

30 A further object is to provide a brooder ventilation structure comprising a closed chamber with a plurality of crates therein, each crate having at least one open side for receiving air from within the closed chamber and a means being provided for exhausting air from another side of the crate and discharging it outside of the closed chamber, whereby air exhaled by the fowls in the crates is not circulated through the closed chamber.

35 Still a further object is to provide means for heating the air that is introduced into the

closed chamber, whereby the brooder structure is suitable for winter use.

Still another object is to provide a means for selectively controlling the flow of ventilating air through each crate.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

40 Figure 1 is a perspective view of a brooder structure embodying my invention.

Figure 2 is a horizontal sectional view on the line 2—2 of Figure 1 illustrating the construction of the crates and associated parts within the closed chamber of the brooder structure.

45 Figure 3 is a vertical sectional view showing the damper arrangement for controlling the ventilation of the various crates in which the fowls are kept.

Figure 4 is an enlarged sectional view on the line 4—4 of Figure 2 illustrating details of the damper control; and

50 Figure 5 is a diagrammatic view showing a larger brooder ventilation structure with additional heating units and crates.

On the accompanying drawings, I have used the reference character A to indicate generally a brooder house. The brooder house has a closed chamber 10 and a heating chamber 12 may be provided in which to house a heating unit, unless some other source of heating means, such as steam pipes or the like from the heating plant of an adjacent building can be utilized.

55 Within the closed chamber 10 of the brooder house A a battery of crates B is located. The battery of crates B, as illustrated on the drawings, consists of a plural- 60 ity or series of crates having open sides 14 65

and perforated sides 16, the perforations of which are indicated at 18.

The open sides 14 may be made of heavy wire, spot welded together and each is preferably provided with a door 20 for gaining access to the interior of the crate. Feeding troughs are indicated at 22. Each crate is provided with a mesh bottom 24 beneath which a removable dropping pan 26 is located.

Imperforate ends 28, top 30 and bottom 32 are provided for each vertically arranged plurality of crates 14. A suitable supporting framework is provided for the parts 14 to 32 and includes supporting legs 34 for supporting the battery B of crates 14 above the floor 36 of the closed chamber 10.

It will be noted that two vertical tiers of crates 14 are illustrated in Figures 1 and 2 with their perforated sides 16 slightly spaced from each other. The space between these sides is closed in by end members 38, a top member 40 and a bottom member 42. The members 38, 40 and 42 constitute a manifold 25 in communication with the crates 14 through the perforations of the sides 16 of the crates. One of the end members 38 is provided with an openable door 40 for cleaning purposes.

For each crate 14 a sliding damper plate 30 46 is provided having a control knob 48. Each damper plate 46 is slidably mounted against the perforated side 16 of the crate by means of brackets 50. Each damper plate is provided with a plurality of damper 35 openings 52 adapted to control the flow of air through the perforations 18, depending on the position of the damper plate openings relative to the perforations.

Connected with the manifold formed of 40 the walls 38, 40 and 42 is an exhaust pipe 54 communicating with a discharge fitting 56. For instance, the exhaust pipe 54 may communicate with an attic space 58 formed in the brooder house A with the fitting 56 in 45 turn communicating with the attic.

I preferably provide a forced draft means 50 for the exhaust pipe 54, such as a motor 60 and a fan 62. The bottom 42 of the manifold is provided with inlet openings 64 with 55 which a damper plate 66 coacts. The damper plate 66 is provided with a control knob 68 and is slidably guided in guide members 70. Damper openings 72 are formed in the damper plate 66.

Outside atmospheric air may be introduced 60 into the closed chamber 10 through any suitable opening and the air may be heated in winter if desired and for this purpose I provide a heating means in the heating compartment 12. For instance, a hot water or steam radiator 74 may be built into an air pipe 76 and hot water or steam may be circulated through the radiator from a boiler 78.

65 Supply and return pipes 80 and 82 are il-

lustrated for connecting the heating boiler 78 with the radiator 74.

If desired, a motor 84 and fan 86 may be provided for causing a forced draft through the air supply pipe 76. The boiler 78 may 70 be fired by oil or gas or any other fuel desired. It is preferable to control the heat of the air passing through the air supply pipe 76 and this may be done by means of a thermostat 88 subject to the heat from the air 75 stream flowing from the supply pipe 76 and through the radiator 74. The thermostat 88 may be located within the closed chamber 10 and may control an oil or gas supply valve 80 90 through a cable connection 92. Where a fuel, such as coal, is used the thermostat control would of course have to be associated with draft and check dampers.

Practical operation

85

In the operation of the ventilating mechanism, air is withdrawn from the manifold between the crates 14 of the battery B so that any air entering the crates from the closed compartment 10, whether introduced thereinto in a heated state or at outside atmospheric temperature, is promptly discharged to atmosphere instead of being circulated through the closed compartment and inhaled by other fowls after once passing through the crates. 90 The temperature within the crates can be controlled to some extent by adjusting the damper plates 46, which is especially desirable where fowls of different ages are placed 95 in the different crates. 100

It will thus be obvious that the fowls in each crate breath only fresh air and a system of ventilation is provided which eliminates the spread of disease, as caused by inhalation of foul air, after it has been breathed by other fowls and all odors are promptly carried away. Automatic means is provided for controlling the temperature of the air and by arranging the manifold so that it collects air from all of the crates it is possible to evenly 105 distribute the circulating air through the plurality of crates. 110

To remove any cold air which has collected adjacent the floor 36 the openings 64 are provided in the bottom member 42 of the manifold and the flow of air through these 115 openings can be readily regulated by adjusting the damper plate 66. In Figure 5 I have shown a diagrammatic view in which a large closed chamber 10a is provided and a plurality of four crate batteries B are arranged therein with branch discharge pipes 92 leading to a common discharge pipe 54a in which the exhaust fan 62a is mounted. If, one heating boiler 78a is found insufficient for the purpose of properly heating 120 the air in the closed chamber 10a, two heating chambers 12a may be provided with a heating boiler located in each one.

Some changes may be made in the con- 130

struction and arrangement of the parts of my device without departing from the real spirit and purpose of my invention, and it is my intention to cover by my claims, any 5 modified forms of structure or use of mechanical equivalents, which may be reasonably included within their scope.

I claim as my invention:

1. In a housing for small animals, a chamber, a tier of compartments therein spaced from the walls of the chamber so as to be substantially insulated from such walls by the air in the chamber and arranged to allow access to the compartments of caretakers inside the chamber, each compartment being adapted to hold a plurality of small animals, pumping means for supplying fresh air to the chamber, an air conductor arranged to receive foul air directly from the small animal compartments and to convey it away so that none of such foul air can return to the chamber or compartments, each compartment communicating with the chamber and serving as a separate passage for air travel 25 from the chamber to the conductor.

2. In a housing for small animals, a chamber, a tier of compartments therein spaced from the walls of the chamber so as to be substantially insulated from such walls by the air in the chamber and arranged to allow access to the compartments of caretakers inside the chamber, each compartment being adapted to hold a plurality of small animals, pumping means for supplying fresh air to the chamber, means for regulating the temperature of the air in the chamber, an air conductor arranged to receive foul air directly from the small animal compartments and to convey it away so that none of such foul air can return to the chamber or compartments, each compartment communicating with the chamber and serving as a separate passage for air travel from the chamber to the conductor.

45 3. In a structure of the kind described, a chamber, a tier of compartments therein, each adapted to hold a plurality of small animals, substantially insulated from the walls of the chamber by the air in the chamber and arranged to allow access to the compartments of caretakers inside the chamber, pumping means for supplying fresh air to the chamber, an air conductor arranged to receive foul air directly from the compartments and to convey it away so that none of such air can return to the chamber or compartments, each compartment communicating with the chamber and serving as a separate passage for air travel from the chamber to the conductor, and having damper means for controlling the relative air flow through such compartment to the conductor.

60 65 4. In a structure of the kind described, a chamber, means for maintaining a supply of fresh air under pressure in the chamber, tiers

of animal holding compartments forming batteries spaced from each other, each compartment being adapted to hold a plurality of small animals, a common air conductor formed between the tiers, and communicating therewith to receive foul air directly from the compartments and to convey it away, so that none of such air can return to the chamber or compartments, each compartment communicating with the chamber and serving as a separate passage for air travel from the chamber to the conductor, and means for regulating the relative flow of air through the respective tiers to the conductor.
